UNITED STATES PATENT OFFICE.

JOHN M. DIETERLE, OF ST. LOUIS, MISSOURI.

METHOD OF PURIFYING AIR.

No. 840,756.

Specification of Letters Patent.

Patented Jan. 8, 1907.

Application filed February 16, 1903. Serial No. 143,525.

To all whom it may concern:

Be it known that I, JOHN M. DIETERLE, a citizen of the United States, residing at the city of St. Louis and State of Missouri, have 5 invented certain new and useful Improvements in Methods of Purifying Air, of which the following is a specification.

This invention relates to a method of purifying air.

It is customary in beer-saloons to force air, by means of a pump, either hand or hydraulic, into an air-reservoir and thence into pipes which enter the barrel of beer from which it is desired to draw, which causes the beer to 10 flow out from the beer-pipes which connect the barrel with the faucets at the bar. As the air thus forced into the beer-barrel, if impure, will vitiate the beer and injure its flavor and healthfulness, it is very desirable 15 that the air should be pure. As a matter of fact, the air that is so introduced into the barrels of beer is in common practice simply taken from the vicinage of the pump. Such air is usually very impure, as the pump, if a 20 hydraulic one, is frequently located in the cellar of the building where the saloon is, and the air surrounding same is contaminated by many conditions, while if a hand-pump is used it is usually located adjacent to the bar, 25 and the foul air of the bar-room is drawn into the pump and forced into the beer.

In the drawings, Figure 1 is an interior elevational view of a box containing several parts usually used in connection with dispensing beer in the manner above stated. Fig. 2 is a front elevation of my improved purifying-box. Fig. 3 is a sectional view of the same. Fig. 4 is a section on line 4-4 of Fig. 3, and Fig. 5 is a section on the line 5-5 30 of Fig. 3.

1 indicates one of the side walls of the box, which contains within it the pump 2, purifying-box 3, cleansing-solution box 4, and air-reservoir 5. The pump 2 may be of any desired type; but I have indicated one of the 45 hydraulic class, which is operated by water admitted through the pipe 6 and takes its air through the pipe 7 and forces the air through the pipe 8 into the purifying-box 3, which is 50 of a construction which will be hereinafter more particularly described. The air leaves the purifying-box 3 through the pipe 13 and enters the air-reservoir 5, in which the compressed air is reserved for use and the pressure 55 maintained at any desired number of pounds per square inch, from whence it com-

municates, by means of a suitable connection, to the barrel of beer, (not shown,) which barrel has another pipe running from it to the beer-faucet in the bar, said connections 60 and the bar also not being shown, and the beer is forced out of the barrel through the pipe to the faucet by means of the air-pressure, as above described.

The air enters the air-purifying box 3 65 through the pipe 8 and is conducted through the lower extension of that pipe to a hollow cap 9, connected thereto by screw-threads and having a plurality of perforations 10 therein. The lower portion of the tube 8 70 within the purifying-box 3 passes through a diaphragm 11, which contains a plurality of perforations 12. The air passes downwardly through the pipe 8 and its lower extension within the box 3 and into the hollow cap 9 75 and out of the perforations 10 upwardly through the perforations 12 in the diaphragm 11 and out through the pipe 13, which leads to the reservoir 5.

Beneath the diaphragm 11 is placed a quantity 80 of glycerin, and as the air passes through the glycerin, arising to pass through the perforations 12 in the diaphragm 11, being all the time under pressure, it loses the impurities contained in it during its passage through the 85 glycerin, as well as any water which may have been carried over with it from the action of the hydraulic pump. When it rises above the glycerin, it may either make its escape directly through the pipe 13 or the upper 90 portion of the purifying-box 3 may be filled with a mixture of roasted shale, coffee, hops, &c., for imparting a pleasant aroma to the air, which will be in turn imparted to the beer in the barrel. This flavoring mixture 95 has been fully described by me in an application for patent copending herewith.

It is to be observed that the cap 9 extends substantially over the area of the cylinder bottom, thereby enabling the glycerin throughout its area to act upon the air, inasmuch as the air is thoroughly broken up and separated by said cap and is evenly distributed throughout the area of the glycerin, as distinguished from cases where the air is passed 100 through the glycerin from the end of a pipe, which causes the air to push its way through the glycerin in a steady current or stream, and by reason of the comparative compactness of the air derives little purification by 105 such passage. The perforated diaphragm acts as a strainer, intercepting the air after its 110

passage through the glycerin and preventing egress of any solid matter which the air may be possessed with.

In this application what I claim, and desire to secure by Letters Patent, is—

The herein-described process of preparing air for use in forcing beer from a barrel in vending the same, consisting in the following successive steps, first discharging air under pressure into a liquid mass of glycerin at a multiplicity of points adjacent the bottom of the latter, splitting up said compressed air into finely-divided streams, whereby said streams may individually course upwardly through said glycerin to have the moisture

and impurities removed, then passing said streams of air through a strainer after they have become freed of said glycerin, then passing said air through an aroma-imparting mixture, and finally collecting the air immediately it has left said mixture and while still in a compressed state in a storage receptacle.

In testimony whereof I have affixed my signature, in presence of two witnesses, this 14th day of February, 1903.

JOHN M. DIETERLE.
